COMBINATION TENT AND CANISTER

Sidney L. Perry, Los Angeles, Calif.
(5145 Kelvin Ave., Woodland Hills, Calif. 91364)

Continuation-in-part of design application Ser. No. 12,035,
May 21, 1968. This application June 17, 1969, Ser.
No. 19,838

Term of patent 14 years

Int. Cl. D21—04

U.S. Cl. D88—3

FIG. 1 is a rear, top and side perspective view of a combination tent and canister in an open position, showing my new design;

FIG. 2 is a front, top and side perspective view thereof in an open position;

FIG. 3 is a side elevation view thereof in an open position;

FIG. 4 is a front elevation view thereof in an open position;

FIG. 5 is a rear elevation view thereof in an open position;

FIG. 6 is a rear perspective view thereof in a closed position;

FIG. 7 is a side elevation view thereof in a closed position; the opposite side, not shown in this position, is a mirror image of the side shown; and

FIG. 8 is a plan view thereof in a closed position.

This application is a continuation-in-part of copending application Ser. No. D-12,035, filed May 21, 1968, now Pat. No. D-214,727.

I claim:

The ornamental design for a combination tent and canister, substantially as shown and described.
